1885.

UNITED STATES PATENT OFFICE.

OLIVER H. HICKS, OF CHICAGO, ILLINOIS.

PAPER PACKAGE FOR TOILET AND OTHER PURPOSES.

SPECIFICATION forming part of Letters Patent No. 329,039, dated October 27, 1885.

Application filed August 20, 1885. Serial No. 174,884. (No model.)

To all whom it may concern:

Be it known that I, OLIVER H. HICKS, a citizen of the United States, residing at Chicago, in the county of Cook and State of Illinois, have invented certain new and useful Improvements in Paper-Packages for Toilet and other Purposes; and I hereby declare the following to be a full, clear, and exact description of the same.

10 My invention relates to certain improvements upon packages of the general nature described in Letters Patent of the United States No. 309,717, granted to me December 23, 1884. My former invention consisted, as 15 set forth in the specification of my Letters Patent aforesaid, in laying the several sheets together in such manner as to cause the opposite ends to overlap one another alternately and securing the alternate ends together—as, 20 for example, by a wire—also preferably securing the contiguous sheets together by means of a light adhesive substance, doubling the package so formed upon itself over a stiffening-piece, and securing the package in such 25 doubled position. Thus, in use, when the external sheet is drawn away from the package it draws the next sheet with it sufficiently to cause the end of the latter to hang freely. In practice I find that the package as above con- 30 structed has more or less tendency to slip down upon the securing wires and away from the stiffening-piece as it becomes reduced in size by use; and one of the objects of my invention is to overcome this difficulty.

35 My invention consists in sustaining the sheets of a package of paper doubled, as described, whether the ends of the sheets overlap each other or not, or whether they are secured together or not by means of wire, or 40 whether they are stuck together or not by means of an adhesive substance, by employing a re-enforcing strip, preferably of flexible material, at or near the top of the package, and firmly secured substantially throughout its 45 entire length to the upper edges or margins of the sheets of paper, whereby the latter are held firmly in their original position until drawn off.

50 My invention consists also in the construction which I prefer to employ.

In the drawings, Figure 1 is a front elevation of a package of toilet-paper provided with my

improvement; Fig. 2, a similar view showing a modification; Fig. 3, a sectional view of the latter, and Fig. 4 a sectional view showing another modification.

A is the bundle of toilet or other paper, formed by laying separate sheets upon one another, either with their alternate ends overlapping or with all their ends coincident, and either with or without a securing-wire passed through the margins; and B is a stiffening-piece, over which the package is doubled. This stiffening-piece may, however, be omitted without departing from my invention, though I prefer to employ it.

C is the re-enforcing strip, which I prefer to employ in the form represented in Fig. 1—that is, by gumming it firmly to the upper edges of the sheets forming the package, the strip passing continuously over the line of junction at the top. It will be seen that the re-enforcing strip alone will serve both to hold the separate sheets together and to hold the package in its doubled form; but when applied in this way I generally prefer also to employ wires, passing through the opposite margins of the sheets and connected together at the point of junction, and also to employ a stiffening-piece, B, as represented in my said former patent. When the stiffening-piece is employed, it is preferably provided with a slot or other aperture at or near the top of the bundle, through which the re-enforcing strip is passed. The re-enforcing strip may, however, pass over the top of the stiffening-piece, if desired. The projecting end of the stiffening-piece, when employed, may be provided with a hook or with one or more holes to permit the package to be conveniently hung up, and when the stiffening-piece is omitted a hook or other hanging device may be secured to the upper edge of the bundle itself through the re-enforcing strip when the latter is at the center, which is its most desirable location. It is obvious, however, that more than one re-enforcing strip may be employed, and if two should be employed the most desirable arrangement would be to place them on opposite sides of the center. The re-enforcing strip, moreover, may be of any suitable width from that of the entire bundle down to a narrow band.

The modified form of the re-enforcing strip,

represented in Fig. 2 renders the use of securing-wires wholly unnecessary, and with this form the stiffening-piece may be omitted with no greater disadvantage than with the other 5 form. In this form the re-enforcing strip is made in two parts wedge-shaped in form, each of which is inserted through a wedge-shaped incision, extending through each end of the bundle, and so formed that the broadest part 10 of the wedge will be at the lower end and the narrowest part at the upper end when the package is doubled. The package being doubled upon itself, either over a stiffening-piece or not, the projecting narrow ends are securely 15 gummed or otherwise fastened together, thus holding the package in its doubled form.

As with the other form of re-enforcing strip, the sheets may be laid together with their ends overlapping alternately, or they may be laid 20 together coincidently; but in either case it is desirable to have the sheets gummed together alternately, though not necessary, unless it is preferred to have the removal of one sheet bring down the next to a hanging position.

25 It will be seen that the wedge-shaped strip passing through the wedge-shaped incision in the margin of the package performs the same function as the straight strip gummed to the edges of the paper, the effect in either case 30 being to maintain the package in its original form whatever the quantity removed in use.

The wedge-shaped strip may be coated with 35 gum before insertion into the wedge-shaped incision; but this is not deemed necessary, since the purpose of the wedge shape is to take the place of gum, and therefore if gum is employed upon the strip passed through the incision the wedge shape may, in general, be omitted.

Instead of being formed in one piece and 40 extending across the meeting ends of the doubled package, the re-enforcing strip may be formed in two parts, terminating at or near the meeting ends of the package, and the connection of these ends be effected by other 45 means—as, for example, a wire or ring, as shown in Fig. 4; but such forms are the obvious equivalents of the others described, and are intended to be included equally in my 50 claims.

What I claim as new, and desire to secure by Letters Patent, is—

1. A package of paper doubled upon itself, in combination with a strip secured practically throughout its whole length to the edge or 55 margin of the package at each end thereof, whereby the separate sheets are held in place, and means, substantially as described, for securing the package in its doubled position.

2. A package of paper doubled upon itself, 60 in combination with a re-enforcing strip of flexible material passing across the line of junction of the meeting ends of the package, and secured substantially throughout its whole length to the ends of the package, as set forth. 65

3. The combination of the package of paper A, the stiffening-piece B, over which the package is doubled, and the re-enforcing strip C, passing through an aperture in the stiffening-piece and secured by means of an adhesive 70 substance substantially throughout its whole length to the ends of the package, as set forth.

OLIVER H. HICKS.

In presence of—

MASON BROSS,
EDWARD THORPE.
